WALTER J. WILSON, OF SEWICKLEY, PENNSYLVANIA.

MINING MACHINE.

Application filed December 19, 1921. Serial No. 523,453.

This invention relates to a combined mining and loading machine, and one of the principal objects of the invention is to simulate the picking action of an individual miner in mining coal or the like. Further objects of the invention are: to provide improved means for carrying the cutters into the material to be mined; to provide breaking down means between the cutters; to provide improved means for carrying away the material mined; to provide adjustable means for carrying the cutting chains; to provide adjustable means for confining the material mined until it is withdrawn by the loading mechanism; and in general, to produce the machine herein shown and described.

In the accompanying drawings, Fig. 1 is a plan view of a machine constructed in accordance with the principles of this invention; Fig. 2 is a side elevation of such a machine; Fig. 3 is a section taken on the line 3—3 of Fig. 1; Fig. 4 is a top view of one of the cutter arms; Fig. 5 is a side elevation; and Fig. 6 is a plan view of one of the cutter bits and its holder; Fig. 7 is a section taken on the line 7—7 of Fig. 3; Fig. 8 is a modification illustrating a shoe in place of a wheel for supporting the cutter arms; Fig. 9 illustrates a machine like Fig. 2 with a modified form of cutting arm; Fig. 10 illustrates a modification in which the cutting arms are raised by a separate power device; and Fig. 11 is a plan view of the machine shown by Fig. 10.

In this invention the cutting chains of each arm and the cutting bits of each chain are staggered relatively with respect to the adjacent ones, so that a variable picking action is produced, and in addition, each cutting chain is given a waving movement and also an eccentric oscillating movement so that the chains as a whole are advanced and withdrawn alternately with respect to the face of the work. Each bit link is also provided with a projection which acts as a conveyor pocket to carry the broken-down material to the loading conveyor. The raising or lowering of the cutting arms may be effected by manual or motor power, and suitable driving means and connections are provided for operating the various mechanisms from a single driving motor.

Referring now more particularly to the drawings, a sliding machine frame or pan 1 is provided with a braced cross piece 2 for supporting a roof jack 3 and a machine rack 4. A machine carriage 5 is slidably mounted in the frame, and has a worm gear 6 to engage the rack 4 for moving the carriage in the frame. A motor 7 mounted upon the carriage has a geared connection 8 with a jack shaft 9 upon which is a driving gear 10 connected by a driving chain 11 with a movable driver 12 loosely mounted upon a cross shaft 13. A gear 14 is also mounted upon the jack shaft 9 and it is connected by means of a driving chain 15 with a sprocket 16 upon the cutting chain 17. A clutch 18 controls the engagement of the gear 14 with the jack shaft 9.

On the cross shaft 13 is a feed worm 19 engaging with a gear 20 on a shaft 21 upon which the worm gear 6 is mounted for moving the machine carriage with respect to the frame. At one side of the driver 12 is a driving connection 22 with a winding drum shaft 23 and at the other side is a clutch collar 24 so that the movement of the driver 12 in one direction will engage the collar 24 to drive the shaft 13, and the movement in the other direction will engage the driving connection 22 to rotate the drum shaft 23 in one direction. At the other end of the shaft 13 is a gear 25 which meshes with a gear 26 on a reversing shaft 27, the gear 26 having a clutch 28 for connecting it with a driving connection 28^a attached to the drum winding shaft 23. This connection is for controlling the driving movement of a winding drum 29 mounted upon the shaft 23 and having a friction clutch 30. With this construction it is obvious that the carriage may be moved relatively to the frame in either direction by reversing the direction of the motor 7, and also the carriage 5 may be operated in either direction from the motor without reversing its direction, the gear 19 being driven either directly through clutch collar 24 or reversely through driving connection 22, shaft 23, driving connection 28^a, clutch 28, 26 and 25, the latter being connected to the shaft 13 on which gear 19 is mounted. This permits the cutter chain to run in one direction even though the car-

riage feed is reversed. The cable drum may be wound up by power and payed out, while the motor is stopped, by using the friction clutch. A ratchet 31 and a locking dog 29^a are also provided for holding the winding drum in any desired position.

At the forward end of the carriage 5 are a pair of spaced cutting arms 33 mounted to swing upon the cutting chain shaft 17, and 10 a conveyor belt 34 has a driving connection 35 with the cutting chain shaft which causes the conveyor to be operated whenever the cutting chain shaft 17 is operated. This conveyor is provided with flights 36, 15 it is mounted in the carriage 5 and has one or more guide shoes 37 to guide it in its movement. The bottom of the carriage 5 constitutes the surface upon which the conveyor flights 36 remove the broken-down 20 material, and the forward end 38 of the bottom of the carrier is turned upwardly to receive material from the cutting chains and to guide it into the path of the conveyor flights 36.

25 Each cutting arm 33 comprises side plates 39 with attached bearing plates 40 in which the cutting chain drive shaft 17 is mounted. At the other end of the side plates 39 are bearing plates 41 in which a cross shaft 42 is mounted. There are a plurality of cutting chains 43 for each arm, and each cutter chain is mounted upon a pair of eccentric sprockets 44 and 45 one attached to the cutting chain shaft 17 and the other mounted 35 on the cross shaft 42. A guide plate 46 is attached at the bottom of the side plates 39 and forms a backing for the cutter chains, and at the top of the side plates is a top plate 47, the upper surface of which is wavy 40 or uneven to give the links of the cutter chains an undulating movement as they pass over the plate.

Intermediate the ends of each cutting arm are bearings 48 vertically adjustable in openings 49 in the side plates by an adjusting screw 50. A shaft 51 is mounted in the bearings and carries a plurality of wheels 52 preferably disposed between adjacent cutter chains and constituting a means for adjustably supporting the cutting arms upon 50 the floor of the mine.

Each cutter chain comprises a plurality of bit links 53 and intermediate connecting links 54. Each bit link has a socket to receive a cutter bit 55, either straight or inclined to one side, the different bits being alternated in accordance with well known practice. A fastening device 56 is provided for removably securing any bit in a socket. 55 Projecting rearwardly from each bit link is an extension 57, the outer end 58 of which is turned upwardly but below the upward projection of the bits 55, and the sides 59 of the extension are inclined outwardly from 60 the bits forming pockets or carriers of

greater width for transporting the mined material with the cutter chains. At the sides of the sprockets 45 between the cutter chains are wedges 45^a to break down the material between the cutter chains.

Extending over the rear portion of each cutting arm is a fixed cover 60, and at the forward end of each arm is a movable telescoping extension 61, the forward depending sides being cut away and the front end 62 75 being bent inwardly, as shown more clearly in Figure 2, so that the extension will engage the uncut material directly over the cutter chains and will be pushed inwardly by such engagement. Resilient means is also provided tending to move the extension 61 forwardly. This means may comprise a pair of brackets 63, one mounted on the cover 60 and the other on the extension 61. A rod 64 extends through the brackets and has 80 headed extremities for preventing disengagement therefrom, and surrounding the rod between the brackets is an extensible spring 65. The extension 61 is therefore pressed inwardly by engagement with the 85 wall of the mine and is pressed outwardly by the spring 65, so that the cutter chains are substantially covered at all times. This confines the mined material to the covered trough thus provided, reduces the dust and 90 forms a more efficient carrier for depositing the material in the path of the conveyor 34. The extension 61 may also be provided with trap doors or hinged portions 61^a at the forward end which may be swung back to provide clearance for the cutter arms. 95

At the inner side of each cutting arm is a projection 66, connected by a shaft 67 with a cable 68 connected thereto and fastening upwardly over a fixed pulley 69 mounted in 100 upstanding fixed arms 70. The cable passes rearwardly over the winding drum 29 which may be operated in either direction as previously explained. In some cases, as for instance when the outer end of the cutter arm 110 is swung upwardly toward the roof of the mine, the extension 61 might prevent the arm from moving upwardly as far as desired and in such case the hinged portion may be swung back to allow for such movement of the arm.

Instead of having elevating wheels 52 for each cutting arm, sliding shoes 71 may be provided, as shown in Fig. 8, adjustably mounted as previously explained on an adjustable cross bearing.

In the construction shown in Fig. 9 the cutting arm is provided with fixed concentric sprockets 72 at the underside over which the cutter chains will pass, the end sprockets 44 and 45 being eccentrically mounted as previously explained, and the cutter chains passing over the wavy plate at the top of the cutting arm. This construction makes a triangular or inclined bottom cut and the 125

operation is the same as though the elevating wheels 52 were removed and the lifting is done by the reel cable 68 or by the action of the cutter arm. A straight cutter arm 5 started in at an angle will not cut the proper clearance for the second cut. With the construction of Fig. 9 the machine carriage is first advanced and then the cutting arm is raised by the cable. In the construction of 10 Fig. 2 the forward movement of the machine carriage causes the proper cut to be made, the cutting arm riding upwardly in the cut made by the cutter chains on wheels 52, or sliding shoes 71.

15 In the construction shown by Figs. 10 and 11, a straight cutting arm 73 may be raised as before explained, by a cable 68 which passes over a fixed pulley 69, but instead of being connected to the power operated winding drum 29, a manually operated winding drum 74 is mounted between side standards 75 which are carried by the sliding frame 1, and upon this drum 74 the cable 68 is wound by means of a hand winding gear 76 which 25 has holding dogs 77. A friction drive which may be similar to that shown in connection with the winding drum 29 controlled by a hand wheel may also be provided, to let the cable 68 pay out as the machine carriage is fed inwardly so that the cutting arms 73 will not start to raise until desired or such paying out may be done manually by the manual winding means for the drum 74. The reason for this is apparent as the 30 standards 75 are fixed and the machine carriage as well as the arms 70 are movable, and as the cable 68 passes over the pulley 69 at the top of the arm 70, the forward movement of the carriage will cause the cutting arm 73 to raise which might not be desired at that time although the height of the cut is controlled by the raising or action of the cutting arms. This is the way the 35 vertical cut is made in this form, as no supporting wheels are provided for the cutting arms.

40 The mounting of the winding drum 74 in the standards 75 must be at a height above all the machinery on the carriage 5 so that the carriage can pass freely between the standards. At the top of each standard a roof jack 80 is commonly provided to give 45 additional stability to the machine frame 1.

50 In the construction thus described, the cutting arms are spaced apart a distance approximately equal to the width of their cut so that in cutting a passage they are inclined first at one side of the passage, as indicated in Fig. 1, and then at the other, thus making sufficient clearance for the machine and for the cutters themselves. The 55 eccentric mounting of each cutter chain is staggered or alternated with respect to the adjacent one; the bits of each chain are staggered or alternated with respect to their

path of cutting; and all of the chains are subjected to the wavy movement produced by the top plate of the cutting arms.

The shape of the cutting arm should be chosen to best accomplish the feeding action 70 and the angle at which the arm is first fed into the material to be mined will determine the depth of the cut. By having the arm curved at the bottom the number of cutting bits engaged is increased, tending to overbalance the pressure of those above at the top and end, and in this way to feed or assist in feeding the arm upward into the material to be mined. The overhanging material above the top bits is relieved and will 75 be broken off in large coarse cuttings. The operation is therefore an intermittently continuous picking action and all the material including that between the cuts is wedged or picked by an action which thus approxi- 80 85 mated that of an individual miner.

I claim:

1. In a mining machine, a movable carriage, a cutting arm pivoted at the front end of the carriage and movable in a vertical 90 plane, a conveyor also mounted in the carriage and comprising a bottom plate with an upward extension just below the inner end of the arm, a movable belt with flights thereon engaging the plate to move material 95 rearwardly, and cutting means carried by the arm for depositing mined material at the inner end of the arm and on the upward extension of said plate.

2. In a mining machine, a movable carriage, a conveyor on the underside thereof, a cutting arm pivoted for vertical movement at the forward end of the carriage, cutting means carried by the arm and movable to discharge breakdown material over the upper side of the arm and in the path of the conveyor, and a common drive for the cutting means and the conveyor comprising a drive shaft concentric with the axis of the cutting arm and a double connection therefrom one to operate the conveyor and the other extending to a power operated means on the carriage. 100

3. In a mining machine, a vertically movable cutting arm pivotally supported at one end, a driving shaft concentric with the pivotal support, a cutter chain movable upon the arm, and a driving wheel which is mounted eccentrically on its axis for driving the chain from a constant movement of the driving shaft. 105

4. In a mining machine, a cutter chain, a continuous driver therefor, sprocket wheel on said driver for moving the chain, the pitch line of said sprocket wheel being at different distances from the axis although it is constantly impelled by the continuous driver. 115

5. In a mining machine, an endless cutter chain, an eccentric support therefor, and 120 125

- continuous driving means which gives the chain an irregular movement because of said support.
6. In a mining machine, a cutter chain, a pair of eccentric sprockets upon which the chain is mounted, and means for operating the chain.
7. In a mining machine, a plurality of endless cutter chains, a separate eccentric mounting for each chain, and a common means for driving the chains.
8. In a mining machine, a cutter chain, a pair of sprockets upon which the chain is mounted for irregular movement, and a support for the chain between the sprockets having an uneven surface for engagement by the chain.
9. In a mining machine, a cutting arm comprising a plurality of cutter chains, a pair of eccentric sprockets for each chain and a support for the chains between the sprockets comprising an uneven surface upon which the chains slide.
10. In a mining machine, an endless cutter chain mounted on the eccentric sprockets, a support for the chain between the sprockets comprising an uneven surface upon which the chain rides.
11. A cutter arm for a mining machine having driving and guiding wheels, a cutter chain mounted on said wheels, and an undulating track for supporting the chain intermediate of the wheels whereby the chain will be given an undulating movement as it passes along the track.
12. In a mining machine, a vertically movable arm pivoted at one end, a plurality of cutter chains mounted on the arm for movement in vertical planes, and adjustable supports between the chains and intermediate the ends of the arm for predetermineding the height of the cutter chains from the floor at this point.
13. In a mining machine, a cutting arm pivoted at one end, a plurality of endless chains, separate eccentric supports for the chains at each end of the arm, adjustable means intermediate the ends of the arms for supporting and guiding it, a common driver for the chains, and a support at the top of the arm having an uneven surface engaged by the chains for further varying their movement.
14. In a mining machine, a vertically movable arm, an endless chain carried thereby comprising bit links with an upstanding rearward projection, means at the top of the arm for confining broken down material, and driving means for the chains whereby the said projections will convey the broken down material with the chain through the confining means and deposit the material at the inner end of the arm.
15. In a mining machine, the combination with a plurality of parallel endless chains each comprising bits staggered with relation to the adjacent bit in the same chain and in adjacent chains, and wedging means carried by the arms to break down the material between the chains.
16. In a mining machine, the combination with a plurality of parallel chains, of staggered bits carried by the chains, and separate means for alternately advancing and withdrawing each chain relatively to the adjacent one.
17. In a mining machine, a cutting arm comprising a plurality of parallel endless chains, means for imparting an intermittent advancing movement to each chain at the end of the arm, and means carried by the arm for independently imparting to each chain an undulating movement between the extremities of the arm.
18. In a mining machine, a cutting arm pivoted for movement about one end, a plurality of parallel endless chains, means for moving the chains for variable advancing movement at the outer end of the arm, and means for bodily moving the arm.
19. In a mining machine, a cutting arm comprising a plurality of cutting chains mounted for variable movement on the arm, means for moving the arm, a cover for the arm extending over the top of the chains and comprising a spring pressed telescoping section adapted to engage the wall of the material to be mined at the side of the arm and to substantially cover the upper portion of the chains outside of the cut made thereby.
20. In a mining machine, a frame, a carriage movable thereon, a cutting arm pivoted at the front of the carriage, means for moving the arm in a vertical plane, a plurality of endless variably movable chains carried by the arm, and adjustable means for supporting the arm at the bottom thereof, a spring pressed telescoping cover for the top of the arm, a conveyor movable with the carrier and terminating at the bottom thereof just below the inner end of the arm, and means in connection with each chain for carrying mined material with the chains through the cover and depositing the material in the path of the conveyor.

WALTER J. WILSON.
